UNITED STATES PATENT OFFICE

2,641,470

DEVICE FOR HOLDING COILS OF STRAPPING WITH MEANS FOR DELIVERING LENGTHS THEREFROM

Anton J. Friedl, Chicago, Ill., assignor to United States Steel Corporation, a corporation of New Jersey

Application August 12, 1949, Serial No. 109,952

4 Claims. (Cl. 271—23)

1

This invention relates to a cage for mounting on a hand truck adapted to receive and support coils of strapping in position for feeding out lengths therefrom and, in particular, to a hand truck body capable of holding a pair of coils and provided with means for feeding a length from either coil or both, selectively.

Steel strapping is used extensively for the purpose of staying or securing loads in place in or on railway cars, as well as for binding boxes, coils of strip and the like. For these purposes, it is necessary to take a coil of strapping and the necessary tensioning and sealing tools to the point of use. It is accordingly an object of the invention to provide an improved coil-holding cage for a hand truck which is simple and economical in construction and efficient in operation.

A further object is to provide a cage adapted to stand erect and support a pair of coils of strap of various widths.

A still further object is to provide manually operable means for feeding strap selectively off of either coil or both.

Further objects, novel features and advantages will become apparent from or be expressly pointed out in the following detailed description and claims.

In a preferred embodiment, I provide a two-wheeled hand truck with a cage or open-sided box adapted to receive a pair of coils of strapping in spaced side-by-side relation. The coils are supported on a pair of spaced rollers journaled in the box. A driving roller common to both coils is journaled near the bottom of the box and is operated by a hand crank mounted at the top of the box. A pressure roller for each coil is normally urged into cooperative relation with the driving roller. A pair of cams on a common shaft serve selectively to actuate one of said pressure rollers to a retracted position.

A complete understanding of the invention may be obtained from the following detailed description and explanation which refer to the accompanying drawings illustrating a preferred embodiment. In the drawings,

Figure 1 is a partial vertical section with parts in elevation;

Figure 2 is a partial section taken along line II—II of Figure 1 with parts in elevation and parts omitted;

Figure 3 is a partial side elevation with a portion in section along line III—III of Figure 1; line I—I of Figure 3 indicates the plane on which the section of Figure 1 is taken.

2

Referring in detail to the drawings, a coil holder or cage 18 is adapted to be mounted on a conventional two-wheeled hand truck. It comprises spaced front and rear rectangular frames each including side rails 19, upper cross rails (not shown) and lower cross rails 21 and 21'. Spacer bars 23 extend between the frames at the top and bottom thereof, respectively. Feet 24 secured to bottom bars 23 enable the truck to stand erect as shown in Figures 1 and 3, when tilted on its wheels to that position.

A coil of strap such as indicated at 32 (Figure 1) may be disposed between each of the front and rear frames of the coil box and the adjacent spacer rods 30. Coils so disposed are rotatably supported on spaced rollers 33 and 33' journaled on shafts 34 and 34', respectively, extending between the lower cross rails 21. Clearance rods 19' are welded on the inner faces of rails 19 for the sides of the coils of strapping to bear against, thus permitting free rotation of the coils without binding or excessive friction. As shown in Figure 1, the coils are so disposed in the box as to feed their free ends from the bottom toward the right. A bar 35 bridging the cross rails 21 and secured to the lower edges thereof supports the ends of the strapping coils after they pass rollers 33' on clockwise rotation of the coils. They are then ready for counterclockwise rotation to feed off the desired lengths from the coils.

A driving roller 36 is mounted on a shaft 37 extending between the bottom cross rails 21' and journaled therein. Shaft 37 is adapted to be driven through a chain-and-sprocket drive 38. When the end of a coil of strapping is pressed into frictional engagement with driving roller 36, rotation of the latter by means of a crank (not shown) will feed the coil end out onto the floor or ground toward the right in Figure 1, between upper guides 41 and 41' and a supporting plate 42 extending between righthand side rails 19 and welded thereto.

Pressure rollers 43 and 43', one for each strapping coil, are journaled in the downwardly extending bifurcated arm of a bell crank 44 journaled on shaft 34'. The downwardly extending arm is designated 44'. Each bell crank also has a horizontal arm 44' which is constantly urged counterclockwise as viewed in Figure 1 by a spring-pressed plunger 45 reciprocable in a bore in a housing 46. The housing is seated on the upturned ends of plate 42 between the righthand side rails 19 and is secured to the latter. 55 The plungers 45 thus tend to cause pressure roll-

ers 43 to force the ends of the strapping coils into frictional contact with driving roller 36.

A cam shaft 47 journaled in the right-hand side rails 19 above housing 46 has eccentrics or cams 48 and 48' spaced therealong and an operating foot lever 49 projecting laterally from one end thereof. As shown in Figure 1, the cams are angularly displaced in opposite directions from an intermediate radius of shaft 47 whereby rotation thereof in one direction as by raising lever 49 causes one of the bell cranks 44 to be tilted clockwise so that its pressure roller releases the coil end. Similarly, rotation of the shaft in the other direction as by lowering lever 49, causes the other pressure roller to release the end of the other coil. Thus, when the lever 49 is in neutral or horizontal position, strapping will be fed out from both coils on rotation of roller 36. When the lever is raised, strapping will be fed from only one coil and when it is lowered, only from the other coil.

The operation of the truck and its appurtenances will doubtless be clear from the foregoing but will be briefly recapitulated. With the truck standing vertically on its wheels and feet 24 as shown in Figures 1 and 3, the spacer rods 30 are adjusted, if need be, to accommodate the strapping coils to be used. When the rods have been set to the proper spacing from the clearance rods 19', the coils are loaded sidewise into the box 18 and placed on rollers 33, with their free ends at the bottom and extending to the right as seen in Figure 1. The coils are then turned clockwise by hand until their ends pass roller 33' and rest on bar 35. The coils are then turned counterclockwise to feed their ends toward driving roller 36. The pressure rollers 43 and 43' are raised successively by tilting cam-shaft lever 49 first upwardly and then downwardly, to permit the ends of the two coils to be threaded between their pressure roller and the driving roller.

With the coils thus placed and threaded, clockwise rotation of shaft 37 will cause roller 36 to feed out strapping from both coils if lever 49 is in neutral or horizontal position. If the lever is tilted up, strapping will be fed out only from the front coil since pressure roller 43' will be raised thereby. Conversely, strapping from the rear coil only will be fed out when lever 49 is tilted down. As strapping is fed out from either coil, it strikes guide 41, then supporting plate 42 and is held down by guide 41'. If an excess length of strapping has been delivered, it may be drawn back to the extent necessary before shearing, by reverse rotation of shaft 37. When it is desired to move the truck to another location, it is only necessary to tilt it to a suitable angle for travel and push or pull it along on its wheels.

The invention has numerous advantages. The cage is light in weight, easily portable and simple and economical in construction. All the working parts may be actuated while the operator stands erect, no stooping or bending being required except to pick up the strapping length when sheared off. The cage and coil-supporting rollers 33 and 33' effectively confine the coils yet permit easy rotation thereof to deliver lengths of strapping as desired. Loading and threading of the strapping coils may be accomplished quickly and easily. The coil selector lever 49 may be operated by the operator's foot to either extreme position. It is self-centering in neutral position by reason of the pressure exerted on the bell cranks 44 by plungers 45.

I claim:

1. Apparatus for feeding elongated material from coils thereof comprising a driving roller adapted to be peripherally engaged by the free ends of the material unwound from the coils, a lever for each coil pivoted adjacent said roller, a pressure roller journaled on each lever cooperating with said driving roller and adapted to press the free end of one coil of material against it, a spring engaging each lever and constantly tending to tilt it and move the pressure roller toward the driving roller, and a shaft having lever-tilting portions spaced therealong and also spaced angularly from each other about the axis of the shaft and thereby being engageable selectively with said levers and adapted to tilt them against the force of said springs.
2. The apparatus defined by claim 1 characterized by said levers including a pair of bell cranks side-by-side, and said shaft having a cam thereon for each bell crank adapted to tilt the cranks respectively, to move their pressure rollers away from the driving roller.
3. The apparatus defined by claim 2 characterized by said cams being spaced angularly in opposite directions from an intermediate radius of the shaft so as to be effective, respectively, on rotation of the shaft in opposite directions from a neutral position.
4. In an apparatus for feeding elongated material from a plurality of coils thereof disposed side-by-side, a driving roller over which the free ends of the coils are adapted to travel, means for rotating said roller to feed the end of any coil which may be frictionally pressed against the roller, a plurality of pressure rollers arranged end-to-end in coaxing relation to the driving roller, means mounting said pressure rollers for independent movement toward and from the driving roller, spring means engaging said mounting means and urging the pressure rollers toward the driving rollers, and a manually operable shaft having angularly displaced cams spaced therealong adapted to cooperate, respectively, with the mounting means of each of the pressure rollers and selectively retract the latter from the driving roller, said shaft being movable into one of a plurality of positions to retract a selected one of the pressure rollers.

ANTON J. FRIEDL.
